DESIGN FOR AN AUTOMOBILE HAT AND COAT HANGER

Oscar W. Kimsey, Atlanta, Ga.

Application July 27, 1945, Serial No. 121,021

Term of patent 14 years

(Cl. D17—12)

To all whom it may concern:

Be it known that I, Oscar W. Kimsey, a citizen of the United States, residing at Atlanta, in the county of Fulton and State of Georgia, have invented a new, original, and ornamental Design for an Automobile Hat and Coat Hanger, of which the following is a specification, reference being had to the accompanying drawing, forming a part thereof.

The figure is a perspective view of an automobile hat and coat hanger, showing my new design.

I claim:

The ornamental design for an automobile hat and coat hanger, as shown.

OSCAR W. KIMSEY.
